UNITED STATES PATENT OFFICE

2,101,465

STORAGE CABINET

Harry F. Beers, Pelham, N. Y.

Application March 22, 1935, Serial No. 12,424

5 Claims. (CL 312—189)

This invention relates to storage cabinets and particularly to the provision of means for sealing the door or doors of such cabinets to render the interior of the cabinet air-tight; and the object of the invention is to provide a cabinet, the door opening of which is provided with a continuous channel in which is supported a strip of sealing material preferably in the form of sponge rubber which is exposed through the channel to be engaged by the peripheral edges of a door or doors controlling access to the cabinet, the strip having beveled edges which form a neat and finished boundary corner or edge to the opening of the cabinet, facilitating cleaning thereof; a further object being to provide means in the form of wedge or cam-shaped bolts for forcing the door or doors inwardly into engagement with sealing strips of the cabinet to insure a positive seal and closure together with a similar locking means for securing the doors in closed position; a further object being to provide a cabinet of the class described having a double wall structure principally at the top, bottom and side walls and on the door or doors employed; a further object being to provide means for sealing adjacent edges of a double door structure to provide an air-tight compartment within the cabinet; and with these and other objects in view, the invention consists in a device of the class and for the purpose specified, which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a face view of a cabinet made according to my invention showing one door thereof in open position and with part of the construction broken away.

Fig. 2 is a horizontal section through the cabinet on an enlarged scale with parts of the construction broken away.

Fig. 3 is a partial section on the line 3—3 of Fig. 1 with parts of the structure broken away; and,

Fig. 4 is a sectional detail view of a part of the cabinet with the door in open position.

My invention, while applicable to cabinets or containers of various kinds and classes where it is desired to provide an air-tight or substantially air-tight compartment therewithin, deals primarily with the construction of cabinets used in

the storage of birds and other animal life as well as matter or products subject to decomposition unless maintained in a hermetically sealed cabinet or container, and wherein the animal life or the like have been treated for preservation, and wherein, in some cases, preservative chemicals or the like are employed in the cabinets to maintain the preservation.

To illustrate one method of carrying my invention into effect, I have shown in the accompanying drawing a cabinet 5, the open side of which is closed by two doors 6 and 7. The cabinet 5 is constructed from substantially similar top, bottom and side walls 8, 9, 10 and 11 respectively. These walls are composed of inner and outer sheet metal parts with an air space 12 therebetween. The rear end portions of said walls include reinforcing strips 13 forming supplemental corner pockets or chambers 14. The back wall 15 of the cabinet consists of a single sheet secured to the other wall portions in the manner clearly seen in Fig. 2 of the drawing, it being understood that all of the sheet metal wall portions are riveted, welded or otherwise secured together in such manner as to form air-tight connections therebetween.

At the front ends of the walls 8, 9, 10 and 11 are secured angle iron strips 16, which in conjunction with inturned flanges 17 and 18 of the separate sheets of the wall portions 8, 9, 10 and 11 form channels in which are arranged sealing strips 19 having beveled exposed surfaces 20 extending outwardly through the opening of the cabinet. These beveled surfaces present smooth and clean boundary walls to the opening of the cabinet and at the same time form relatively thick central body portions to said strips facilitating greater compression thereof.

Angle iron strips 16 are reinforced by other angle iron strips 16a to give strength and rigidity to the front edge portions of the cabinet. The arrangement of the angle iron strip 16 is such as to form a chamber or clearance space 21 between it and the outer wall to receive one of the butts 22 of a number of hinges 23. The other butts 24 of said hinges are attached to the outer walls 8a, 1a of the doors 6 and 7 and these attachments are reinforced by channeled reinforcing strips 24a disposed within the chambers of the doors 6 and 7 or between the outer plates 6a, 7a and the inner plates 6b, 7b thereof.

At this time it is well to point out that the purpose of the double wall structure is not only to give strength and rigidity to the resulting cabinet, especially in using a light sheet metal

structure, but also to insure against any possible leakage of air, especially through the coupling and fastening means which, as later described, are mounted on the front walls 6a, 7a of the doors. The peripheral edges of the inner surfaces of the doors are provided with inwardly projecting beads 25 which also form the means for joining the walls 6a, 6b, 7a, 7b together as will appear upon a consideration of Figs. 2 and 10 3 of the drawing.

The hinged side walls of the doors 6 and 7 are also provided with V-shaped extensions 26, note Fig. 2 of the drawing, which provide a double seal of the doors in connection with the sealing strip 19 and at the same time, reinforce and strengthen said edges of the doors. The strip 19, which may be one continuous strip or a series of strips adhered together at the intersections thereof, is preferably composed of rubber or 15 sponge rubber but may be composed of any suitable yielding material suitable for the intended purpose.

It is also desirable to seal the adjacent edges of the doors 6 and 7. For this purpose, I mount 25 on the inner surface of one door, the door 6 in the construction shown, an elongated channeled strip 27, the channel of which is directed outwardly and in which a thin sealing strip 28 is mounted. The channel terminates within the 30 boundaries of the inner surfaces of the top and bottom walls 8 and 9, whereas the ends of the strip 28 are allowed to overlie the sealing strip 19 as indicated at 28a in Fig. 1 of the drawing to insure a seal at the upper and lower corner portions 35 of the doors where they intersect at adjacent edges. The strip 28 is adapted to be compressed by the bead or flange 25 of the door 6 when placed in the channel 27, whereas the bead or flange 25 of the door 7 engages this strip to 40 effect a seal in the manner indicated in Fig. 2 of the drawing.

Pivoted mounted on the outer plates or walls 6a, 7a of the doors 6, 7 are handles 29 and 30, each carrying within the chambers of the doors 45 plates 31 and 32. Coupled with these plates are upwardly directed links 33, 33a which are pivoted to upper cam or wedge-shaped latch bolts 34, one of which is shown in detail in Fig. 3 of the drawing. Pivoted to the plates 31 and 32 are 50 similar downwardly extending links 35, 35a which are pivoted to other cam or wedge-shaped latch bolts 34a. The bolts 34 and 34a are guided in channel-shaped brackets 36 arranged within the chamber of the doors 6 and 7, and said bolts extend through the upper and lower surfaces of 55 the doors and enter apertures formed in adjacent portions of the upper and lower walls 8 and 9 of the cabinet, one of the apertures being indicated at 37 in Fig. 3 of the drawing. The wall 60 portions of the cabinet where the latch bolts 34, 34a pass therethrough, are reinforced by L-shaped bolts 38. Pivoted to the plate 32 is a short link 39 to which is pivoted a latch bolt 40 similar to the bolts 34, 34a, the bolt 40 passing 65 through a U-shaped guide 41 within the chamber of the door 7 and entering an aperture in the adjacent wall of the door 6.

The plates 31 and 32 are rotatable with the 70 handles 29 and 30, and in opening the doors 6 and 7, the plates are moved into the position shown at the right of Fig. 1, in which position, the bolts 34, 34a of the door 7 are drawn into the chamber of the door, whereas in closing the doors, the plates assume the position shown at the 75 left of Fig. 1, in which position, the bolts 34, 34a

are projected and engage the apertures of the top and bottom walls 8 and 9.

The cam surfaces or wedge-shaped ends of the bolts serve to force the doors 6 and 7 inwardly to tensionally engage the sealing strip 16 5 and strip 28. The bolt 40 also aids in this respect to draw the adjacent edges of the doors 6 and 7 together or to force the bead 25 of the door 7 into firm engagement with the strip 28.

With the foregoing construction, the doors 6 10 and 7 may be positively sealed within the cabinet and with their adjacent edges sealed to form an air-tight closure for the compartment in order to maintain the desired preservative conditions or characteristics of the compartment. In this 15 connection it will be apparent that the design of cabinet disclosed is intended for storage of a number of cabinets back to back, with the flush rear surfaces of the cabinet in abutting relation, thus eliminating the necessity of a double 20 wall structure, but in other types of cabinets, the double wall structure may be carried throughout the back wall, as will be apparent. If desired, suitable insulating material may be placed in the 25 chambers of the hollow wall structure of the cabinets and doors, especially in adapting the cabinets for use in preserving articles placed therein from a standpoint of temperature.

In the construction shown, the opposed side 30 walls 10 and 11 are provided on the inner surfaces thereof with a plurality of vertically spaced cleats 42 formed from a corrugated sheet of metal, only part of the cleats being shown in Fig. 1 of the drawing for purposes of simplification.

A number of box-shaped trays 43 may be supported on the cleats 42, three of which trays are shown in Fig. 1 of the drawing. The trays have at their lower edges outwardly extending flanges 44 which are adapted to seat upon the cleats 42. However, the arrangement of trays or shelves 40 within the cabinet may be modified to suit the particular use of the cabinet and to adapt it for storage of articles, products or animal life of various kinds and classes.

In certain uses of the cabinets, the same will 45 be placed one upon the other. To facilitate alignment thereof, the upper surfaces will be provided with two or more upwardly extending disc-like beads 45 adapted to enter corresponding recesses 46 formed in the lower wall of an 50 adjacent cabinet. The side, top and bottom walls of the cabinet may also be reinforced by a number of U-shaped reinforcing strips 47 such as indicated in the side walls in Fig. 2 of the drawing, especially when the sheet metal employed on the cabinet is comparatively thin.

Having fully described my invention, what I claim as new and desire to secure by Letters Patent, is:—

1. A cabinet of the class described having 60 sealed top, bottom, side and back walls, the front of the cabinet being open, the peripheral edges of the top, bottom and side walls of the cabinet adjacent the front opening having a continuous channel arranged within the front 65 surface of the cabinet, a strip of sponge rubber arranged in and extending throughout the length of said channel, said strip being substantially triangular in cross sectional form with the thick part of said strip arranged centrally of the 70 channel, a closure for the opening of said cabinet, said closure having projecting flanges adapted to engage said strip throughout the peripheral edges of the closure to form an air-tight connection between the closure and said 75

cabinet, and means movably mounted in connection with the closure and engaging the cabinet to forcibly move the projecting flanges of the closure into firm engagement with said strip.

5. 2. A cabinet of the class described having a sealed top, bottom, side and back walls, the front of the cabinet being open, the peripheral edges of the top, bottom and side walls of the cabinet 0 adjacent the front opening having a continuous channel arranged within the front surface of the cabinet, a strip of sponge rubber arranged in and extending throughout the length of said channel, said strip being substantially triangular 15 in cross sectional form with the thick part of said strip arranged centrally of the channel, a closure for the opening of said cabinet, said closure having projecting flanges adapted to engage said strip throughout the peripheral edges 20 of the closure to form an air-tight connection between the closure and said cabinet, means movably mounted in connection with the closure and engaging the cabinet to forcibly move the projecting flanges of the closure into firm engagement 25 with said strip, and the boundary walls of said channels having inturned flanges engaging side edges of said rubber strip to retain the same against displacement.

3. A cabinet of the class described having a 30 door opening and a closure member for closing said opening, a sealing strip for forming a seal between the walls of the cabinet at the door opening and said closure member to provide a substantially air-tight mounting of the closure member in the cabinet, said strip comprising an elongated body of rubber substantially triangular in cross sectional form, opposed contracted side edges of said strip terminating in mounting portions having substantially parallel opposed 35 surfaces and means on the walls of the cabinet engaging the mounting portions of said strip for supporting the strip in connection with the cabinet.

4. The combination with a cabinet and a closure for an opening in said cabinet, of means for 40 forming a seal between the cabinet and closure,

said cabinet and closure being provided one with a continuous channel and the other with a projecting flange adapted to enter said channel, said channel consisting of wall portions arranged at right angles to each other, the free edges of 5 the wall portions having hook-shaped strip retaining flanges and a sealing strip of cushioning material having walls disposed at right angles to each other to fit snugly upon the right angle walls of said channel, the free side edges of the 10 strip terminating in projecting parts engaged by the hook-shaped sides of said channel to retain the strip against displacement therefrom, and the exposed surface of said strip extending between the hook-shaped flanges being arranged at 15 approximately 45° to the walls of said channel to provide a thick freely yieldable central portion to said sealing strip adapted to be engaged by the first named flange.

5. The combination with a cabinet and a closure for an opening in said cabinet, of means for forming a seal between the cabinet and closure, said cabinet and closure being provided one with a continuous channel and the other with a projecting flange adapted to enter said channel, 20 said channel consisting of wall portions arranged at right angles to each other, the free edges of the wall portions having hook-shaped strip retaining flanges and a sealing strip of cushioning material having walls disposed at right angles 25 to each other to fit snugly upon the right angle walls of said channel, the free side edges of the strip terminating in projecting parts engaged by the hook-shaped sides of said channel to retain the strip against displacement therefrom, the 30 exposed surface of said strip extending between the hook-shaped flanges being arranged at approximately 45° to the walls of said channel to provide a thick, freely yieldable central portion to said sealing strip adapted to be engaged by 35 the first named flange, and said cabinet and closure being provided with interengaging means for retaining the closure in closed position and for forcibly moving the first named flange into 40 engagement with said sealing strip.

45 HARRY F. BEERS.
